UNITED STATES PATENT OFFICE.

CHARLES L. GOODRUM AND EDWARD E. HINRICHSEN, OF NEW YORK, N. Y., AS/IGNORS
TO WESTERN ELECTRIC COMPANY, INCORPORATED, OF NEW YORK, N. Y., A COR-
PORATION OF NEW YORK.

METERING SYSTEM FOR PARTY TELEPHONE LINES.

Application filed July 6, 1921. Serial No. 482,713.

To all whom it may concern:

Be it known that we, CHARLES L. GOODRUM and EDWARD E. HINRICHSEN, citizens of the United States, residing at New York, in the county of New York, State of New York, respectively, have invented certain new and useful Improvements in Metering Systems for Party Telephone Lines, of which the following is a full, clear, concise, and exact description.

This invention relates to telephone systems and more particularly to telephone systems wherein a number of stations are branched off from a common circuit.

Its object is to provide means for automatically and positively determining which one of the branch stations is connected to the common circuit.

It is particularly adapted for and is shown embodied in a party line arrangement for machine switching telephone systems, and provides means whereby upon the initiation of a call the proper meter at the central office is positively connected with the metering circuit.

In accordance with this invention as applied to party line metering, the stations are equipped with relays adapted to be operated by currents of different character successively applied from the central office upon the initiation of a call by a switch which is set in motion upon the initiation of the call and at each step applies to the line a current of different character, and also at each step connects a different meter to the metering circuit, this switch continuing in motion until the proper current is applied to operate the relay of the calling station, the operation of this relay causing the switch to stop, with the corresponding meter connected to the metering circuit. This metering circuit may be subsequently closed in any suitable manner. In the present instance, it is closed automatically during the breaking down of the connection.

Referring to the drawings, Fig. 1 shows the invention embodied in a machine switching telephone exchange system; Fig. 2 shows the details of a polarized relay, one of which is provided for each station.

Only so much of the circuit is shown as is necessary for a comprehension of the invention. The polarized relay 5 of substation

1 is positively polarized. The polarized relay 6 of substation 2 is also positively polarized and in addition is marginal. The polarized relay 7 of substation 3 is negatively polarized. The polarized relay 8 at substation 4 is also negatively polarized and in addition is marginal. It is thought that the invention will be most readily understood from a detailed description of the operation.

Upon the removal of the receiver at substation 1 the switchhook in rising closes the contact 9 thus connecting the positively polarized relay 5 to ground from the tip side 10 of the line, and the closure of contact 11 completes a loop circuit for the line relay 12 at the central office. Relay 12 in attracting its right armature closes a locking circuit for itself to ground at the right armature and back contact of the cut-off relay 13, and also closes at its outer left armature a circuit for the stepping magnet 14 of the meter selector which is provided with brushes 15, 16 and 45. Brush 16 does not bridge the normal and first contacts, but bridges on all other steps. The attraction of the outer left armature of the line relay 12 also prepares a circuit for the start relay 17 to start an idle line finder LF in search of the calling line as described in detail in Patent No. 1,193,053, issued August 1, 1916, to L. Polinkowsky. Magnet 14 advances the meter selector one step from its normal position to position 1, whereupon the prepared circuit for the start relay 17 is closed. In position 1 of the meter selector switch, relay 18 operates in a circuit including brush 16, the tip side of the line 10, contact 9, through the relay 5 to ground. Relay 18 in attracting its outer right armature operates relay 19 in a circuit including contact 20 of cam 21 of the meter selector and the upper two windings of the relay 19 in series. Relay 19 in attracting its lowermost armature closes a locking circuit for relay 18 including the inner right armature of said relay, and at its upper armature closes a substitute circuit for magnet 14 including the outer right armature of relay 18, whereupon magnet 14 steps the switch to position 2. In moving out of normal position, cam 22 opens contact 23. Thus magnet 14 is dependent for its next energization upon

the circuit leading through the contacts of relays 19 and 18. In moving out of position 1 cam 21 of the meter selector opens contact 20 and in position 2 positive current is applied through the upper two windings of relay 19 in series and brush 16 to the tip side 10 of the line, from which relay 5 is branched off to ground. This relay responds to this current and in attracting its armature opens contact 24. The mechanical construction of the relay 5 is such that this contact is held open for a period long enough to allow relay 19 to release, which releases relay 19. The release of relay 18 opens the circuit of the stepping magnet 14 to stop the selector with the brush 15 connecting meter 25 of substation 1 to the metering conductor 26, and although relay 19 again energizes, relay 18 remains inert. The mechanical construction of relay 5 may be as shown in Fig. 2. The armature 40 is provided with an arm 27, which when the armature is attracted moves a lever 28 to the right to allow the spring 29 to rotate a lever 30 in a counter clockwise direction to open the contact 24, thus disconnecting the magnet 5 from ground whereupon it releases, the spring 31 in retracting the armature 40 causing the arm 46 to rotate the lever 30 in a clockwise direction, and the spring 32 forcing the lever 28 back to its original position. The line finder LF upon reaching the calling line multiples, closes a circuit including sequence switch contact 32, inner left armature and normal contact of relay 18, for the cut-off relay 13, which in attracting its right armature opens the locking circuit of relay 12, and in attracting its left armatures cuts off the meter selector from the calling line and extends the line through to the repeating coil RC. The connection is now established as described in the above mentioned patent and upon the breaking down of the connection sequence switch contact 33 is closed which closes a circuit including the outer right armature of the relay 12, and the right armature and alternate contact of relay 13, conductor 26, brush 15, (position 2) and the meter 25, which meter operates and advances the counting train 34 one step.

The meter selector switch may be restored to normal upon the breaking down of the connection in any suitable manner, as shown for example in Patent No. 1,135,011, to C. L. Goodrum, patented April 13, 1915. The cutoff relay may be used for this purpose and would correspond to the magnet M^{23} of Fig. 9 of said patent. This relay upon deenergizing withdraws the holding pawl as shown and described in detail in said patent.

If station No. 2 initiates a call, positively polarized marginal relay 6 is connected to ground from the tip side 10 of the line and

the meter selector switch is started in operation as described in the case of station 1. The meter selector switch will continue stepping until it reaches position 3 because the relay 6 being marginal, does not receive sufficient current in position 2 over both of the windings of relay 19 in series. In position 3, however, only the lower winding is connected to the brush 16 and consequently relay 6 operates disconnecting ground from the tip side 10 of the line resulting in the release of the relays 19 and 18 and the stopping of the meter selector with meter 35 connected to the meter conductor 26 by the brush 15.

In case station No. 3 initiates a call the negatively polarized relay 7 is connected to the tip side 10 of the line and the meter selector will continue stepping until it reaches position 4, at which time negative current is applied through the lower windings in series over brush 16 to the tip side of the line to ground through the relay 7 which in operating removes ground from the tip side of the line, resulting in the release of the relays 18 and 19 and the stopping of the meter selector with the brush 15 connecting the meter 36 to the metering conductor 26.

If the station No. 4 initiates a call the negatively polarized marginal relay 8 is connected to ground from the tip side 10 of the line, and in this case the meter selector will continue stepping until it reaches position 5, because relay 8 being marginal as well as polarized will not operate over both lower windings in series, but will only operate in position 5 in which position negative current through the lowest winding only is connected through brush 16 to the tip side 10 of the line. Relay 8 in operating removes ground thus releasing relays 19 and 18, resulting in the stopping of the selector with the meter 37 connected to the meter conductor 26 over the brush 15.

If a call is initiated by the closure of the loop circuit at the calling station but no ground is present, the meter selector will move into position 1 and will stop since relay 18 will not operate due to the tip side 10 of the line being ungrounded. A signal lamp 38 is connected to this contact and will indicate to an attendant the abnormal condition. If there is a permanent ground on the line the meter selector will continue stepping until it reaches position 6. In this position a lamp 39 is lighted which indicates this abnormal condition.

By virtue of the present invention it will be seen that the meter corresponding to the calling station is automatically positively connected to the metering circuit upon the initiation of a call; that the possibility of operating the wrong register or the subscriber "beating" the apparatus is

very remote and that abnormal conditions in the circuit are automatically indicated.

What is claimed is:

1. In a party line metering circuit arrangement, a meter for each station at the central office, sources of current of different character at the central office, a metering circuit, means for automatically connecting the proper meter to the metering circuit upon the initiation of a call comprising a number of relays one at each station adapted to be selectively operated by currents of different character from said sources, a switch set in motion by the initiation of a call and at each step applying to said line a current of different character, and at each step also connecting a different meter to the metering circuit, said switch continuing in motion until the proper current is applied to operate the relay at the calling station, means controlled by said relay in operating to stop said switch with the corresponding meter connected to the metering circuit, and means for thereafter closing said metering circuit.

2. In a party line metering circuit arrangement, meters at the central office, a metering circuit, sources of current of opposite polarity at the central office, a polarized relay at each station, a resistance at the central office connected to said sources of current, a switch set in motion upon the initiation of a call and applying current from said sources through different points of said resistance to said line until the proper polarity and strength of current is applied to operate the polarized relay at the calling station, means controlled by said relay for stopping said switch with the proper meter connected to the metering circuit, and means for thereafter closing said metering circuit.

3. In a party line metering system, meters at the central office, a metering circuit, a step-by-step switch at the central office adapted to connect said meters to the metering circuit, means for grounding the line, and for starting said switch in motion upon the initiation of a call, a relay at the calling station for removing said ground when the switch reaches the meter of the calling station to stop said switch with said meter connected to said metering circuit, and means for thereafter closing said metering circuit.

4. In a party line metering system, meters at the central office, a metering circuit, a switch at the central office adapted to connect said meters in the metering circuit, means for starting said switch in motion upon the initiation of the call, means for grounding the line upon the initiation of a call, a relay at the calling station for removing said ground when the switch reaches the meter of the calling station to

stop said switch with said meter connected to said metering circuit, and means for thereafter closing said metering circuit.

5. In a party line metering system, meters at the central office, a metering circuit, a step-by-step switch at the central office adapted to connect said meters to the metering circuit, means for starting said switch in motion upon the initiation of a call, a polarized relay at each station, means for grounding the line through the relay of the calling station upon the initiation of a call at said station, sources of positive and negative current at the central office, means at the central office comprising a relay having a number of windings through which current from said sources is applied to the calling line by said switch until the proper polarity and strength of current is applied to operate the polarized relay of the calling station to remove said ground, means controlled by the removal of the ground for stopping said switch with the proper meter connected to the metering circuit, and means for subsequently closing said metering circuit.

6. In a party line metering system, meters at the central office, a metering circuit, a step-by-step switch at the central office adapted to connect said meters in the metering circuit, means for starting said switch upon the initiation of a call, sources of current of opposite polarity at the central office, means for stopping said switch with the proper meter connected to the metering circuit comprising a polarized relay for each station on the line and a relay at the central office through the windings of which current from said sources is applied to operate the relay of the calling station to stop the switch, and means for thereafter closing said metering circuit to operate the selected meter.

7. The combination with a telephone line, a pair of stations thereon, a central office, a meter at the central office for each station, a metering circuit, a step-by-step meter selector having one brush for connecting said meter with said metering circuit, a source of positive current at the central office, a relay having a pair of windings, a positively polarized relay at one of the stations, a positively polarized marginal relay at another of the stations, means for connecting the relay of the calling station to ground from one side of the line and for starting said switch upon the initiation of a call, said switch on its first step applying current to said line, first through both windings of said relay in series and on its second step through one winding only to selectively operate said polarized relays, means for maintaining said switch in motion as long as said ground is applied, said current operating the polarized relay of the calling sta-

tion and causing said ground to be removed to stop said switch with its brush connecting the corresponding meter to said metering circuit, and means for subsequently closing said metering circuit.

8. The combination with a telephone line, two pairs of stations thereon, a meter at the central office for each station, a metering circuit, a step-by-step meter selector switch, 10 having one brush for connecting said meters with said metering circuit, a source of positive and a source of negative current at the central office, a relay at the central office having two pairs of windings, a positively 15 polarized relay at one of the stations, a positively polarized marginal relay at another station, a negatively polarized relay at the third station and a negatively polarized marginal relay at the other station, 20 means for connecting the polarized relay of the calling station to ground and for starting said switch, said switch on its first step applying positive current to said line through two windings in series, on its second step through one winding only, on its 25 third step applying negative current through two windings in series and on its fourth step through one winding only to selectively operate said relays, means for 30 maintaining said switch in motion until the

relay of the calling line operates and removes the ground, whereby the proper meter is connected to the metering circuit by said switch, and means for subsequently closing said metering circuit.

9. In a telephone system, a common circuit, a number of branch circuits, sources of current of different character, electro-responsive devices, a circuit for operating the same, means for connecting the proper device to the said common circuit comprising a relay at each of the branch circuits adapted to be selectively operated by currents from said sources, and a switch set in motion by the closure of the common circuit at any branch circuit and at each step applying to said common circuit current of different character and at each step connecting a different device to said operating circuit until the proper current is applied to operate the relay of the calling branch circuit, means controlled by said relay in operating to stop said switch with the corresponding device connected to the operating circuit, and means for operating said device.

In witness whereof, we hereunto subscribe our names this 30th day of June, A. D. 1921.

CHARLES L. GOODRUM.
EDWARD E. HINRICHSEN.
